PUMPING APPARATUS

John Mann, Seneca Falls, N. Y., assignor to
 Goulds Pumps, Inc., Seneca Falls, N. Y., a corporation of New York

Application September 5, 1941, Serial No. 409,708

3 Claims. (Cl. 103—5)

My invention relates to pumping apparatus or systems and more particularly to pumping systems of the so-called jet type. Reference is made to my copending applications Serial Number 326,445 filed March 28, 1940, issued Sept. 30, 1941, as Patent No. 2,257,507, and Serial Number 394,838 filed July 30, 1941.

In the above mentioned applications I have shown and described pumping systems of the so-called jet type adapted for either shallow or deep well use. The systems shown in the above mentioned applications employ a vertically mounted pressure or centrifugal pump. The invention of the present application embodies most of the principles disclosed in the above mentioned copending applications, the primary differences being those required to provide an arrangement wherein the pressure or centrifugal pump is mounted in a position with its axis of rotation substantially horizontal. I have found that a number of economies in the over-all cost of the system may be effected by employing a horizontally mounted pressure or centrifugal pump as distinguished from a vertically mounted pressure pump.

An object of my invention is to provide a pumping system of simple construction which may be produced at an appreciably lower cost than the pumping systems of the prior art.

Another object of my invention is to provide a pumping system wherein the pressure or centrifugal pump is mounted in such a position that it rotates about a horizontal axis which, in particular when the system is for shallow well operation, enables a convenient, compact and efficient mounting of the jet pump with respect to the centrifugal pump.

Another object of my invention is to provide improved and simplified means for substantially hydraulically balancing the pressure or centrifugal pump.

A further object of my invention is to provide a pumping system in which the pressure or centrifugal pump is mounted with its axis of rotation horizontal and which comprises the combination of a jet pump, a pressure pump, an air separating chamber and other elements so constructed and arranged as to prevent the recirculation of air through the pressure or centrifugal pump.

My invention further contemplates the provision of a pumping system of the so-called jet type which is arranged so that it may be readily converted to a deep well jet pump system, a shallow well pump system or so that the jet pump

may be entirely eliminated to the end that the system may operate as a straight centrifugal pump.

Other objects and advantages of my invention will be apparent from the following description, when taken in connection with the accompanying drawings, in which:

Fig. 1 is a general assembly view, somewhat diagrammatic, illustrating the pumping system of my invention when set up for shallow well operation;

Fig. 2 is a vertical sectional view through the pump unit of Fig. 1;

Fig. 3 is a view similar to Fig. 1 illustrating the system as set up for deep well operation;

Fig. 4 is a vertical sectional view of the pump unit when set up for deep well operation as illustrated in Fig. 3;

Fig. 5 is a view taken substantially on the line 20 5—5 of Fig. 4 in the direction indicated by the arrows; and

Fig. 6 is a view showing a portion of Fig. 4 and illustrating how the system may be set up so as to operate as a straight centrifugal pump.

25 In Fig. 1 I have shown the pumping system of my invention as set up for shallow well operation. As thus arranged the system comprises a pump unit, generally indicated by the numeral 11, a motor 12 for driving the pressure or centrifugal pump of the pump unit, a pneumatic pressure tank 13 and a suction pipe 14 which extends into the well. The pump and motor, if desired, may be mounted on a suitable bed plate 15.

One of the advantages of employing a system 35 wherein the pressure or centrifugal pump rotates about a horizontal axis is that horizontal motors are considerably cheaper than vertical motors. This is due to a major extent to the larger production of horizontal motors as compared with the production of vertical motors. A further advantage of employing a horizontal pumping unit lies in the compact arrangement of parts which may be effected, particularly when the unit is arranged for shallow well operation, and still embody the essential principles and advantages disclosed in my above mentioned copending applications.

As shown in Fig. 2 the pumping unit 11 comprises a shaft 16, driven from the motor 12, upon 50 the end of which is mounted the pressure or centrifugal pump impeller 17. While I have shown a pump of the centrifugal type, if desired, a regenerative turbine pump or a so-called water ring pump may be used. While the centrifugal pump impeller may be of conventional construc-

tion for purposes which will later appear, a somewhat special type of centrifugal pump impeller is preferably employed.

The shaft 16 extends through a bearing assembly, generally indicated by the numeral 18, and through an opening provided in the rear half 19 of the pump casing, generally indicated by the numeral 21. On the shaft 16 may be mounted any suitable means for preventing creepage of liquid along the shaft such as a water slinger 22 together with any desired means of substantially sealing the casing at the point where the shaft extends therefrom. The above parts may be conventional and need not be more particularly described herein.

The casing 21 in addition to the rear half 19 includes a front half or plate 23. Either or both halves of the centrifugal pump casing may be provided with an opening or openings serving as an outlet or outlets for the liquid discharged from the centrifugal pump. Preferably the rear half 19 of the pump casing is provided with two oppositely disposed discharge openings which may be similar in construction, shape and arrangement to the discharge openings shown in my above mentioned copending applications.

Facing upon and secured to the rear half 19 of the pump casing as shown at 24 and 26 is a cover or housing plate or casting 27. The cover or housing plate 27 is preferably of hollow shape so as to provide an enlarged chamber 28 into which the centrifugal pump discharges through the outlets provided in the pump casing. The chamber 28 is of sufficient size and capacity to appreciably slow down the velocity of the liquid discharged into it so as to permit liquid and air separation to take place therein. The air separation chamber 28 is intended to serve essentially the same function as the double air separating chambers shown and described in my above mentioned copending applications.

Because the velocity of the liquid is decreased to a considerable extent in the air separating chamber 28, the pressure therein is considerably higher than in the pump casing 21. The decreased velocity of the liquid permits the air to separate from the liquid and collect at the top of the chamber from whence it flows, together with liquid, through an opening 29 and a pipe assembly 31 to the pneumatic tank 13. It will be noted that the outlet from the air separating chamber is preferably placed substantially at the top thereof so that any air separated in the chamber will flow through the pipe 31 to the pneumatic tank and not accumulate in the chamber.

Supported preferably by the cover plate 27 is a jet pump assembly, generally indicated by the numeral 32. The jet pump assembly comprises a jet 33 and a diffuser 34 which are arranged in axial alignment in the conventional manner. In the drawings I have illustrated the diffuser as being cast integral with the cover plate 27 and have shown the jet threaded into the wall 36 which forms part of the support for the diffuser. However, if desired the diffuser may be a separate element from the cover plate and may be threadedly supported as shown in my above mentioned copending applications. The portion of the casing which forms the support for the jet and the diffuser is arranged so as to provide a separation wall between the air separating chamber 28 and a suction chamber 37. The suction chamber 37 is provided with an opening 38 which is connected as shown in Fig. 1 to the suction pipe 14.

Thus in accordance with the disclosures of my above mentioned copending applications, liquid is discharged by the centrifugal pump, flows into the air separating chamber 28 in which space the air and liquid are separated. Air free liquid then flows downward through the air separating chamber and at high velocity through the jet and diffuser so as to create a sub-atmospheric pressure in the suction chamber 37. The reduced pressure in the suction chamber 37, resulting from a combination of the affects produced by the jet pump and the centrifugal pump, causes liquid to flow from the well through the suction pipe and into the annular space surrounding the jet 33. It will be noted that the liquid enters the jet near the bottom of the chamber so that before the liquid reaches the jet substantially all of the air has been removed from it.

The centrifugal pump is provided with a substantially axially located cylindrical member 41 which forms the suction opening or eye of the centrifugal pump impeller. In the preferred form of my invention the cylindrical suction member 41 is somewhat extended so as to receive in concentric relation therewith, the end of the diffuser 34. The cylindrical member 41 is arranged so that the annular space between it and the outer circumference of the diffuser is as small as possible. This annular space 42 constitutes an annular leakage opening through which liquid may flow from the point of higher to that of lower pressure. In this instance the liquid pressure in the air separation chamber 28 is higher than that at the suction opening so that a small amount of leakage liquid flows through this annular space into the suction of the centrifugal pump.

The front half 23 of the pump casing 21 is provided with an opening through which the cylindrical suction member 41 extends. This opening is defined by a circular surface 43. The clearance between the rotating cylindrical member 41 and the circular surface 43 is also made as small as possible. Both this clearance and the clearance at 42 being in the neighborhood of $\frac{1}{1000}$ of an inch. Thus, since the pressure in the air separating chamber 28 is higher than that in the pump casing 21 a slight leakage of liquid occurs through the space between these parts from the air separating chamber 28 to the pump casing.

The primary purpose of the above arrangement is, as described in the above mentioned copending application, to prevent liquid discharged from the pump from recirculating to the suction of the centrifugal pump without passing through the air separating chamber 28. It will be observed that any liquid passing through these passages, particularly the passage 42, has the air removed from it so that air leaking into the system, purposely admitted to the system or drawn in with the liquid pumped cannot recirculate or accumulate in the centrifugal pump or in the system. The arrangement shown effectively seals the pump casing from the impeller suction inlet.

One of the problems encountered in pumping systems of the character disclosed in this application is that frequently sandy water must be handled. This sand tends to lodge in the close clearances provided between the rotating and fixed parts. I have found that this difficulty can be eliminated, as disclosed in my copending application Serial Number 394,838, by arranging a screen between the air separating chamber 28 and the suction of the pump. For the purpose of mounting the screen the front half 23 of the

casing is provided with an annular boss or ring 46 which extends around the suction opening, as more clearly shown in Fig. 5. An annular eccentric plate 47 is carried by the annular boss 46 and between the annular plate and the boss the screen 48 is confined. The parts may be held in position in any suitable manner as shown in the drawings.

The opening 49 in the plate permits free access of the liquid from the air separating chamber 28 to the space on the right-hand side of the screen, as viewed in Fig. 2. As previously mentioned, the plate is eccentric so that the lower portion thereof, as indicated at 51, extends substantially to the bottom of the chamber. The plate constitutes a baffle for directing the flow of liquid. Thus any liquid discharged, for example, into the space 52 from the pump casing must rise and flow around the annular boss 46 substantially to the top of the air separating chamber 28 before it can pass through the screen 48 and gain access to the suction opening. The plate 51 extends close enough to the bottom of the chamber so that any liquid passing through the space 53 is substantially air free.

One of the important aspects of my invention lies in the means for hydraulically balancing the impeller. It will be appreciated that both sides of the impeller are exposed to the pressure existing within the pump casing 21. However, the areas on opposite sides of the impeller over which this casing pressure is exerted are not equal. This is due to the presence on one side of the impeller of the suction opening. In Fig. 2 pressures C and C are equal. While the circular area B is greater than the annular area A, the pressure over the area A is considerably greater than the pressure over the circular area B. Assuming that the pressures on the areas E and D are equal there would be an unbalanced thrust in a direction to the left, as viewed in Fig. 2.

I have found, by properly proportioning the area D that I may take advantage of the higher pressure existing in the air separating chamber 28, as compared to the pressure in the pump casing, to the end that the impeller may be hydraulically balanced. While the pressure in the air separating chamber 28 is somewhat variable, using an average value the area D may be made such, in designing the pump, that the following equation is satisfied:

Pressure on area D $\times$ area D plus pressure on area B $\times$ area B equals pump casing pressure $\times$ (area A plus area E).

It will be appreciated that the pressure varies in the chamber 28 and that the suction pressure and the pump casing pressure are also variables. However, these pressures increase and decrease substantially in proportion. By proper tests average values can be obtained so that the area D may be made the proper amount for maintaining the impeller in approximate hydraulic balance throughout the operating range of the system. The cutout formed in the cylindrical suction inlet 41 is made for the purpose of decreasing the weight of the rotating parts.

In Fig. 1 I have shown a strainer located at the bottom of the jet pump and indicated diagrammatically at 55 a check or foot valve. In application Serial Number 326,445 I have shown the check valve located close to the pump and this arrangement is sometimes preferred for the reasons stated in said application.

In reorganizing the system for deep well operation it would be possible to remove the plug

56 and substitute therefor a pressure pipe. The jet 33 would then be removed and a plug inserted in this opening. A jet and the diffuser would then be located in the well as illustrated in Fig. 3. Substantially this method of converting the system for deep well operation is shown in my application Serial Number 326,445.

I have found, however, the conversion from a shallow well system to a deep well system may 10 be accomplished more readily by substituting for the plate or head 21 a plate or head 58 shown in Fig. 4. The plate 58 is of substantially the same construction as that of Fig. 2 and has the air separating chamber 28 provided therein. 15 However, instead of employing a jet pump in the head, I connect the suction chamber 37 directly with the impeller inlet by a passage 59 formed in the head 58. The pressure pipe 61 is then connected to the opening 62 and the jet pump, 20 indicated generally by the numeral 63, is mounted in the well in the conventional manner. This rearrangement of parts it will be appreciated can very readily be accomplished in the field without 25 a great deal of labor and expense. Thus if the pump owner finds that the well draw down is such that a shallow well pump will not operate properly, he may purchase a new plate or head 58, mount a jet pump in the well and connect the piping, as shown, without any great inconvenience or expense.

In Fig. 3 I have shown below the jet pump a strainer 64 and indicated diagrammatically a check or foot valve 56. If desired the check or foot valve 56 may be located just below the jet 35 pump in the position indicated in the drawings by the numeral 67. While it most frequently happens that it is desired to convert a shallow well system to a deep well system, it will be appreciated that if desired the deep well unit of 40 my invention may be converted to a shallow well unit.

In Fig. 6 I have illustrated how the system may be converted to operate as a straight centrifugal pump. The advantage of eliminating the jet 45 pump if the well characteristics permit, is that the capacity of the system is increased. A portion of the liquid when a jet pump is used must be returned to the jet pump for supplying energy thereto. The effective capacity of the centrifugal 50 pump is decreased by the amount of liquid necessary to feed the jet. Thus if well conditions permit, as for example if the lift is twenty feet, it is desirable to eliminate the jet pump in order to obtain the resulting increased capacity. This 55 may be easily accomplished with the same head or plate 58 shown in Fig. 4. In converting the system to a straight centrifugal pump the pressure pipe 61 is removed and a plug 68 substituted therefor. The suction pipe is mounted as shown 60 in Fig. 1 and the system will operate as a straight centrifugal pump. The straight centrifugal pump may be converted to a shallow well jet system or a deep well jet system in a manner which will be obvious from the above description.

In the drawings I have not shown a pressure control switch for controlling the starting and stopping of the pump so as to maintain the pressure in the pneumatic tank within desired limits. Moreover, I have not shown a means for charging 70 the pneumatic tank with air. These elements may be similar in construction and operation to the corresponding elements shown and described in the above mentioned copending applications. That is, preferably the system is provided with a pressure control switch and with a connection to

atmosphere on the suction side of the pressure pump for maintaining the quantity of air in the pneumatic tank substantially constant.

It will be observed that the air separating chamber is arranged above the pressure pump and since the foot or check valve maintains the liquid in the piping, the pump is at all times flooded. Should leaks develop in the piping, the pump will automatically pick up liquid as long as the chamber 28 is not depleted of liquid. Moreover, should the water in the well drop below the end of the tail pipe so as to permit the tail pipe to become filled with air, the combination of the jet and centrifugal pump will automatically exhaust the air from the piping when the liquid again rises to the proper level with respect to the tail pipe since the air separating chamber is filled with liquid. Thus unless abnormal leaks develop in the system the system will stay primed.

While I have shown and described the preferred forms of my invention and have described how the unit may be readily converted from one type of system to another, it will be appreciated that various changes and modifications may be made, particularly in the form and relation of parts, without departing from the spirit of my invention as set forth in the appended claims.

I claim:

1. In a pumping system, in combination, a pressure pump having a rotatable impeller, said impeller having an axial substantially cylindrical suction opening, and a jet pump comprising a jet and a diffuser mounted adjacent said suction opening with the discharge end of the diffuser extending into said suction opening.

2. A pumping system comprising, in combina-

tion, a pump casing having an inlet, an impeller mounted in said casing with the axis of rotation thereof extending substantially horizontally, an air separating chamber associated with said casing and said casing having at least one outlet for the discharge of liquid from said impeller into said air separating chamber, and a unit detachable with respect to said pump casing without disturbing the pump casing, said unit carrying a nozzle and a diffuser mounted in spaced axial alignment with each other and being in communication with the casing inlet, the nozzle being in communication with the air separating chamber and the space between the nozzle and diffuser being in communication with the source of liquid supply.

3. A pumping system comprising, in combination, a pump casing having an inlet, an impeller mounted in said casing with the axis of rotation thereof extending substantially horizontal, an air separating chamber associated with said casing and said casing having at least one outlet for the discharge of liquid from said impeller into said air separating chamber, and a unit detachable with respect to said pump casing without disturbing the pump casing, said unit carrying a nozzle and a diffuser mounted in spaced axial alignment with each other and being in communication with the casing inlet, the nozzle being in communication with the air separating chamber and the space between the nozzle and diffuser being in communication with the source of liquid supply, and said air separating chamber having a discharge connection for liquid in a fixed part of the system.

JOHN MANN.
